[57] **CLAIM**

The ornamental design for a hand-held communications microphone, substantially as shown and described.

DESCRIPTION

FIG. 1 is a front elevational view of a hand-held communications microphone, showing our new design,
FIG. 2 is a side elevational view thereof, looking from the right side of FIG. 1,

FIG. 3 is a side elevational view thereof, looking from the left side of FIG. 1,

FIG. 4 is a rear elevational view thereof,

FIG. 5 is a top plan view thereof, looking from the top of FIG. 1,

FIG. 6 is a bottom plan view thereof, looking from the bottom of FIG. 1,

FIG. 7 is a front elevational view of a hand-held communications microphone, showing another embodiment of our new design,

FIG. 8 is a side elevational view thereof, looking from the right side of FIG. 7, and

FIG. 9 is a side elevational view thereof, looking from the left side of FIG. 7.

FIG. 1.

FIG. 2.

FIG. 3.

FIG.4.

FIG.5.

FIG.6.

FIG.7.

FIG.8.

FIG.9.
